[57] CLAIM

The ornamental design for a panelled baggage unit, as shown and described.

DESCRIPTION

FIG. 1 is a perspective view of a panelled baggage unit showing my new design with the flap in an opened position;

FIG. 2 is a front elevational view thereof with the flap closed;

FIG. 3 is a rear elevational view thereof;

FIG. 4 is a top plan view thereof;

FIG. 5 is a bottom plan view thereof;

FIG. 6 is a left side elevational view thereof with the flap opened; and

FIG. 7 is a right side elevational view thereof with the flap closed.
